UNITED STATES PATENT OFFICE.

RAYMOND BURNHAM, OF CHICAGO, ILLINOIS.

DISPLAY STAND AND CONTAINER.

Application filed May 26, 1925. Serial No. 33,034.

This invention relates to an improved combined container or box and display stand adapted for containing goods when shipped and to be set up for display and advertising 5 the same as well as facilitating the dispensing thereof or removal from the box or container when on display for sale.

The object of the invention is to provide a novel container of the above character 10 which is made from a single blank of novel construction bent in a novel manner and adjustable to display one or more rows or tiers of articles such as cartons or containers for cosmetics, tooth paste, or the like, in elongated tubes and so constructed that when the 15 upper row of containers or articles is removed, the device may be adjusted to display the lower row or layer with equal facility of vision, so that the contents will not 20 be precluded from view.

A further object of the invention is to provide a combined container and display stand which will not require an extra support or easel for disposing the same in an inclined 25 position in order to display the contents, but will display the same by means of part of the box which also serves to re-inforce the container.

Other and further objects of the invention 30 consist of certain novel combinations and arrangements of parts as will be hereinafter more particularly set forth and described.

Fig. 1 is a plan view of a blank from which 35 the container is made;

Fig. 2 is a perspective view of the container showing the arrangement of articles therein for display and sale;

Fig. 3 is a vertical sectional view of the 40 device showing two rows of packages or articles superposed one upon the other and indicating the facility with which the same may be removed;

Fig. 4 is a sectional plan view partly broken away and showing the manner of folding the blank to produce the container;

Fig. 5 is a vertical sectional view similar 50 to Fig. 3 but with the upper row of articles removed and the device adjusted to display the lower row or series of articles; and

Fig. 6 is an enlarged sectional view taken on the line 6—6 of Fig. 4.

Referring to the drawings in detail, in 55 which like reference characters designate corresponding parts throughout the several views, the container is produced from a

blank shown in Fig. 1 which includes a bottom portion 7 formed with arcuate or outwardly convexed cuts or slits 8 near but slightly spaced from each side to provide 60 tongues 9. The bottom 7 also has side extensions 10 foldable along the dotted or scored lines 11 parallel to the folding lines 12 at the side edges of the bottom and further provided with folding lines 13 forming foldable extension portions 14 of the same width as the portions 10 and integral therewith but provided with narrow extensions or flanges 15 there-beyond at the ends of the side extensions. 70

The opposite sides of the bottom forming the front and back of the container are provided with extensions 16 foldable on the lines 17 and having at their ends, tongues or flaps 18 foldable inwardly at right angles 75 along the lines 19 to overlap each other inwardly of the sides 10, as shown in Figs. 4 and 6 of the drawings. The flaps 18 are of substantially the same length as the parts 16 and 10 and are severed from the parts 80 10 and 14 as indicated at 20, but it is to be understood that the proportions of these parts may vary, especially in accordance with the shape of the container or box. That is, the box may be elongated from front to 85 rear or from side to side instead of being substantially square or may be of any other suitable shape.

One side 16 at the front of the box is provided with a similarly shaped extension 21 90 foldable along the line 22 defining the outer longitudinal edge of the side 16. The extension 21 at its outer edge is provided with a section 23 foldable along the dotted or scored line 24 and corresponding in size and 95 shape to the bottom 7 to form a false bottom and easel or support for the articles or goods, as will be hereinafter pointed out. The section 23 is further provided at its outer edge with a narrow extension 25 foldable on the line 26 parallel to the lines 22 and 24 and another narrow extension 27 corresponding to the section 25 substantially at the free end provided with a central tongue 28 of reduced size or length. It may also be mentioned that the extension 27 is foldable along the line 29. 100 105

At the opposite side 16 corresponding to the back of the container or box, the latter is provided with an extension 30 foldable 110 along the line 31 parallel to the folding line 17 and with a further extension 32 on the

- extension 30, foldable on the line 33, while the extension 32 is provided with a narrow flap or tongue 34 extending throughout the length thereof and foldable on the line 35. 5 The parts 30 and 32 form a top or cover for the container and the folding line 33 is in the center thereof. Both sections 30 and 32 are wider than the adjacent side section 16 and the section 30 is provided with an arcuate slit or cut 36 providing a tongue 37 foldable on the line 33 at the central portion thereof. However, the tongue 37 is quite wide occupying one-third or more of the length of the folding line 33 at its straight 10 edge and producing a tongue of substantially semi-circular shape like the tongues 9. Of course, the length of the tongue or tab 37 may vary.
- In folding the box, the sides 16 are folded upwardly at right angles along the lines 17 and the flaps or extensions 18 are turned inwardly at right angles along the folding lines 19 to overlap one another as shown in Fig. 4 of the drawings. The sides 10 are 15 then folded upwardly at right angles along the lines 12 against the flaps 18 so that the folding lines 11 will embrace the top edges of the flaps 18, after which the flaps or extensions 14 are folded over the top edges 20 thereof and down into and against said flaps 18 at the inside of the container or box. This brings the tongues or flanges 15 against the bottom surface at the inside and they are directed inwardly at right angles so that 25 their free edges will extend beneath the tongues 9, beneath which they are inserted by raising said tongues 9. This retains said tongues in position and re-inforces the sides and holds the box assembled as a container 30 open at the top.
- The front and back or side sections 16 being in vertical position, the extension or section 21 is then folded down into the box and against the section 16 when the box is 35 used as a container for shipping purposes, the parts 25 and 27 together with the tongue 28 being folded along the line 26 beneath the false bottom section 23, which is disposed flat against the bottom surface. The sections 40 30 and 32 will then form the top of the container or box and by turning in the tongues 34 downwardly against the inner face of the side section 21 by folding the sections 30 and 32 as along the line 31, a complete container 45 is thus provided to accommodate one or more rows of articles designated at 38, the latter preferably being two rows arranged in superposed relation.
- However, when the device is used for display purposes as a stand and carton or container, the part 21 is spaced and inclined rearwardly from the adjacent part 16 and false bottom 23 is disposed in an inclined position and folded along the line 26 as 50 shown in Fig. 3 of the drawings, with the parts 27 and 28 folded beneath to form a support or easel for the false bottom. The sections 32 and 34 are then folded forwardly along the line 33 so that the tongue 37 will extend upwardly, thus supporting the boxes 55 70 in superposed relation and in an inclined position with the rear ends thereof spaced from the back of the container, and upright display card thus provided as shown in Fig. 3. It should also be noted that the part 34 75 terminates at or slightly above the folding line 26 of the false bottom, while the part 25 is slightly inclined toward the rear. When the upper row of articles 28 is removed, the lower row may be displayed so 80 as to be readily viewed by prospective purchasers by raising the section 27 substantially in the same plane with the section 25 and turning the tongue 28 under along the line of fold thereof designated at 39, thus raising 85 the false bottom or section 23 to a higher elevation or inclined position whereby the articles will be projected above the top of the container as shown in Fig. 5 of the drawings. This forms a desirable and effective display 90 stand, and the portions 32 and 37 may bear upon the front surface thereof, as well as the surrounding outer surfaces of the walls of the box, suitable price information or advertising relative to the goods contained in 95 the cartons or articles displayed in the container.
- While I have described the invention in its preferred form, it is to be understood that certain changes may be made in the 100 construction and arrangements of parts described, without departing from the spirit of the invention, so long as the same are included within the scope of the claims.
- I claim:
1. A combined container and display stand comprising an open top container structure having an extension at the top edge of the front wall thereof, folded downwardly in an inclined position and then rearwardly in an inclined position to form a false bottom, the free end of the false bottom having a plurality of foldable sections adapted to support said false bottom at different elevations. 105
  2. A combined container and display stand comprising an open top container structure having an extension at the top edge of the front wall thereof, folded downwardly in an inclined position and then rearwardly in an inclined position to form a false bottom, the free end of the false bottom having a plurality of foldable sections adapted to support said false bottom at different elevations, said foldable portions adapted to be folded at different points or extended in a straight line to support the false bottom in its lower and upper positions whereby superposed upper rows of articles or the lower row thereof, may be 110 115 120 125 130

displayed from the top of the container and having an end tongue adapted to be folded forwardly against the bottom of the container to support the same in an elevated position against the back of the container.

3. A combined container and display stand comprising an open top container structure having an extension at the top edge of the front wall thereof, folded downwardly in an inclined position and then rearwardly in an inclined position to form a false bottom, the free end of the false bottom having a plurality of foldable sections adapted to support said false bottom at different elevations, and a back foldable section having a slit in a first foldable portion thereof, foldable with the second foldable portion to extend upwardly above the upper edge thereof when the second foldable portion is folded over forwardly and down against the first foldable portion whereby said slit produces a tongue extending above the top edge thereof.
4. A combined container display carton comprising a blank having a bottom portion with foldable side sections along the edges thereof and bottom slits producing outwardly extending tongues at the bottom, opposite side sections forming the sides of the container having foldable extensions of the same width and said foldable extensions having narrow foldable extensions at the free edges thereof to form flanges adapted to extend beneath said tongues at the bottom of the box when the sides are extending upwardly and the first foldable section turned down against the inside thereof, the other sides corresponding to the front and back of the box having foldable end tongues adapted to be folded in overlapping relation at the sides and against the inner faces thereof over which the first foldable sections are disposed, said front and rear foldable

sections having additional folding sections, the front folding section having a first folding section adapted to be folded downwardly inside of the front section, an integral foldable section corresponding to the bottom and foldable down into the container against the bottom or in an upwardly and rearwardly inclined position, and two successively foldable narrow sections and a tongue at the free edge thereof adapted to be folded beneath said false bottom section or in angular relation at different folding lines to support the false bottom at different elevations, the foldable section corresponding to the back having two successive foldable sections and a narrow foldable flap forming a tongue at the free edge thereof.

5. A combined container display carton comprising a blank having a bottom portion with foldable side sections along the edges thereof, opposite side sections forming the sides of the container having foldable extensions, said foldable extensions having foldable extensions at the free edges thereof to form flanges adapted to engage the bottom of the box, the other sides having foldable end tongues adapted to be folded in at the sides, said second-named foldable sections having additional folding sections adapted to be folded downwardly inside of the front section, an integral foldable section corresponding to the bottom and foldable down into the container against the bottom or in an upwardly and rearwardly inclined position, and two successively foldable sections adapted to be folded beneath said false bottom section to support the false bottom at different elevations, the foldable section corresponding to the back having a foldable flap forming a tongue at the free edge thereof.

In testimony whereof I affix my signature.
RAYMOND BURNHAM.
